UNITED STATES PATENT OFFICE.

STANHOPE BOAL, OF PIQUA, OHIO.

DESIGN FOR A STOVE.

No. 38,041.

Specification for Design.

Patented May 29, 1906.

Application filed April 12, 1906. Serial No. 311,370. Term of patent 7 years.

To all whom it may concern:

Be it known that I, STANHOPE BOAL, a citizen of the United States, residing at Piqua, in the county of Miami and State of Ohio, have invented a new, original, and ornamental Design for Stoves, of which the following is a specification, reference being had to the accompanying drawing, forming part thereof.

The figure is a front elevation of a stove, showing my new design.

I claim—

The ornamental design for a stove, as shown.

STANHOPE BOAL.

Witnesses:

C. WINKELMANN,
OLIVER B. KAISER.
